SWIMMING POOL GUARD

Robert F. Pinckard, Hialeah, Fla.; Dorothy Helen Pinckard, administratrix of said Robert F. Pinckard, deceased

Application January 5, 1955, Serial No. 479,919

1 Claim. (Cl. 4—172)

This invention generally relates to a safety device and more specifically provides a swimming pool guard for positioning in an open swimming pool for the protection of small children.

In certain areas, the provision of private swimming pools on an individual home owner's property is quite common, and it sometimes happens that small children playing in the areas of open swimming pools may accidentally fall into the pools and drown before assistance can be called or before the child is missed. In an attempt to overcome this, certain laws and ordinances have been passed to require that a home owner having a swimming pool must enclose the pool with a fence in order to eliminate the possibility of small children falling into the pools and harming themselves. The provision of a fence in surrounding relation to a swimming pool destroys the esthetic value of the pool as well as cluttering up the pool area. Also, various small animals are prone to fall into the pool and drown, and it then becomes quite expensive to empty and clean the pool. Accordingly, it is a primary object of the present invention to provide a swimming pool guard for preventing small children or stray animals from accidentally falling into and remaining submerged in the pool.

Another object of the present invention is to provide a swimming pool guard including a vertical movable member conforming to the bottom of a swimming pool together with means for automatically raising and lowering the vertically movable member upon actuation of a suitable control.

A further object of the present invention is to provide a swimming pool guard conformable to the preceding object in which the automatically vertically movable member is actuated by the interruption of an electric eye light beam by an object or body passing through the light beam, wherein the light beam is positioned at the open upper end of the pool so that anything falling into the pool will actuate the movable member whereby the movable member will be moved to a position at the upper surface of the water in the pool.

Still another important object of the present invention is to provide a vertically movable member which may be manually controlled so that the movable member may be positioned under the water line of the pool for any suitable depth so that the pool may be converted into a safe wading pool for young children.

Another important feature of the present invention is to provide a swimming pool guard having a movable frame member with netting thereon constructed of two portions for positioning flatly against the double inclined bottom of a swimming pool wherein hoist means is provided for raising the downwardly inclined portions of the frame members faster than the uppermost portions of the frame members so that the frame members are in substantially coextensive and planar relation when raised to the top of a swimming pool.

Other important objects of the present invention will reside in its simplicity of construction, dependability, safety, ease of manufacture and installation, its adaptability for its purposes, and its relatively inexpensive manufacturing and maintenance costs.

These together with other objects and advantages which

2

will become subsequently apparent reside in the details of construction and operation as more fully hereinafter described and claimed, reference being had to the accompanying drawings forming a part hereof, wherein like numerals refer to like parts throughout, and in which:

- 5 Figure 1 is a top plan view of a swimming pool guard of the present invention with portions of the cable housing broken away showing the construction and arrangement thereof;
- 10 Figure 2 is a longitudinal, vertical sectional view taken substantially upon a longitudinal center line of the construction of Figure 1 showing the positioning of the two elements of the movable member resting against the bottom surface of the swimming pool;
- 15 Figure 3 is an enlarged detailed sectional view showing the construction of one of the double pulleys and a right angularly disposed pulley for supporting the lifting cable;
- 20 Figure 4 is a diagrammatic view of the wiring system utilized in actuating the swimming pool guard of the present invention;
- 25 Figure 5 is a longitudinal, vertical sectional view similar to Figure 2 showing the vertically moving members in elevated position;
- 30 Figure 6 is an enlarged, vertical sectional view taken substantially upon a plane passing along section line 6—6 of Figure 1 showing the details of construction of the raising and lowering mechanism for the vertically movable members;
- 35 Figure 7 is an enlarged fragmentary perspective view of a corner of the vertically moving member showing the details of construction thereof;
- 40 Figure 8 is a vertical, sectional view taken substantially upon the plane passing along section line 8—8 of Figure 7 showing the manner of attaching the net or mesh members to the framework of the vertically moving members; and
- 45 Referring now specifically to the drawings, it will be seen that the numeral 10 generally designates the swimming pool guard of the present invention for positioning in an opening defining a swimming pool and designated by the numeral 12. The opening 12 is surrounded by a side wall 14 that is positioned in the ground 16. The side wall 14 is integrally joined by end walls 18, thereby forming a peripheral wall for the swimming pool opening 12. The swimming pool 12 includes an elongated bottom member 20 extending from one end wall 18 towards the other end wall 18, and inclining downwardly therefrom. The bottom wall 20 terminates in spaced relation to the other end wall 18 and is secured thereto by a second bottom member 22 which inclines upwardly to the bottom of the end wall 18. It will be seen that the bottom members 20 and 22, along with the walls 14 and 18 are of a conventional swimming pool construction wherein the bottom slopes inwardly and downwardly from each end wall 18 to a maximum depth in spaced relation to each of the end walls 18 but nearer one end wall than the other end wall. Further, one of the end walls may be longer than the other end wall for providing two different depths of water 24 in the pool 12 at each end thereof. This construction of the swimming pool has been set forth in order to describe the swimming pool guard of the present invention and actually forms no part thereof.
- 55 The swimming pool guard 10 of the present invention generally includes a pair of frame members generally designated by the numerals 26 and 28. Each of the frame members 26 and 28 are formed from a plurality of longitudinal rails 30 that are in spaced parallel rela-
- 60
- 65
- 70

tion and rigidly secured in spaced relation by a plurality of transverse rails 32. The frame members 26 and 28 are independent of each other and each of the frame members 26 and 28 is covered with criss-cross members 34 which form a net or mesh which will permit passage of water therethrough but will not permit passage of objects of any size.

The longitudinal rails 30 and the transverse rails 32 may be constructed of tubular pipe members of standard construction and connected together by suitable pipe couplings, such as L-shaped members 36, T-members 38 and cross-members 40. The longitudinal pipes or rails 30 and the transverse pipes or rails 32 are provided with a plurality of peripheral recesses 42 for receiving rings 44 formed on the ends of the mesh members 34, thereby providing a smooth peripheral surface for the longitudinal rails 30 and the transverse rails 32.

When the swimming pool guard 10 is in its normal position, the framework 26 is disposed flatly against the bottom portion 20 and the framework 28 is positioned flatly against the bottom portion 22 of the pool 12. In order to lift the framework members 26 and 28 from the bottom of the pool 12 to the top thereof, an electric motor 46 is provided with a power shaft 48 having a plurality of drums 50 and 52 thereon which form winches for raising and lowering the frame sections 28 and 26. Secured to the drums 50 and 52 is a series of cables 54, 56, 58 and 60. The cables 54 pass over suitable idler pulleys 62 and 64 and pass downwardly at each corner adjacent one end 18 of the pool and are connected to the outer corners of the framework 28 by a suitable hook 66 which engages over the longitudinal rails 30. The cables 56 pass over suitable idler pulleys 68 and are connected to the corners of the framework 26 remote from the cables 54. The cables 54 and 56 are secured to the smaller and equal sized pulleys so that the movement of the outer ends of the framework members 26 and 28 will be of substantially the same magnitude.

The cables 58 pass over suitable idler pulleys 70 and are secured to the adjacent ends of the framework members 26 and 28 at one side thereof for simultaneously raising the adjacent edges of the framework members 26 and 28. The cables 60 pass over suitable idlers 72 completely down one side of the pool and around to the other side thereof for attachment to the other side of the framework members 26 and 28 at the adjacent edges thereof in opposition to the cables 58. The cables 58 and 60 are attached to the enlarged drums on the rotating shaft 48, thereby raising the sides of the frame members 28 and 26 in unison and moving the adjacent edges of the framework 26 and 28 to a position at the upper edge of the water 24. Due to the fact that the cables 58 and 60 are secured to the larger diameter pulleys or drums, it will be seen that the adjacent edges of the framework members 26 and 28 will move at substantially a faster rate than the remote edges thereof and the movement of the adjacent edges is so related to the movement of the remote edges of the framework members 26 and 28 that both of the framework members 26 and 28 will be disposed in substantially a horizontal plane with the adjacent edges thereof overlapping, as illustrated in Figure 5, when the framework members 26 and 28 are raised substantially to the upper end of the pool 12, thereby assuring that any object within the pool will be disposed above the water surface.

Within the end walls 18 is a plurality of recesses 72 having mirrors 74 in the inner wall thereof for reflecting a light beam 76 emitted by a light 78 and adapted to be received by a photocell 80. This photoelectric set-up is connected to a relay cell 80 which will sound an alarm 82 and start the motor 46 when the light beam 76 is temporarily broken by the passage of an object therethrough. A suitable switch 84 may be provided for connecting the swimming pool guard 10 of the present

invention to a suitable power source and other manual switches 86 and 88 may be provided for manual operation of the motor 46 without utilizing the light beam 76 as a safety device. This is useful in elevating the frame members 26 and 28 to a position spaced below the upper water level of the pool 12 for permitting wading by small children without any danger thereto.

It will be seen that the various cables and pulleys of the present invention are positioned within a longitudinal housing or casing 90, and the pulleys positioned on a horizontal axis at each corner and at each edge of the pool are mounted in a suitable channel-shaped member 92 on a horizontal axis 94, all of which may be of any well known construction. Further, the motor 46 and the various pulleys and shaft are positioned within a housing 96 to prevent possible damage to persons coming into contact therewith.

In practical operation, the framework members 26 and 28 may be constructed of any suitable lightweight pipe, such as aluminum tubing, and the webbing or mesh material may be of any suitable plastic, such as nylon, rubber or of plastic coated copper wire of suitable tensile strength, and is attached to the frame member to form substantially two inch squares. When the electric eye or photocell is activated, the alarm bell will ring and the electric motor will be energized, thereby raising the entire apparatus to a position above the water level of the pool in which the apparatus has been installed. The particular manner in which the various elements are mounted is optional, and other types of lift mechanisms may be utilized for raising the frame members 26 and 28. Further, suitable means may be provided for automatically de-energizing the motor after it has raised the members 26 and 28 to their uppermost position but will permit continuous ringing of the alarm bell, if desired. Additionally, the relatively small weight of the framework members 26 and 28 permits the entire device to be easily raised out of the pool for vacuum cleaning of the pool or permitting other operations necessary in cleaning or repairing the pool.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claim.

What is claimed as new is as follows:

In a swimming pool, a pair of guard frames normally disposed in said pool in downwardly converging edge to edge relation, cable and pulley means connected to said frames for simultaneously elevating said frames out of the pool into horizontal level position, a motor operatively connected to said cable and pulley means, and motor control means comprising a series of mirrors in each of two opposite sides of the pool staggered in one series with respect to the other to reflect a zig-zag beam of light across the pool, a source of light in one side of the pool projecting a beam of light against an end mirror of one series, and a photoelectric cell at said side of the pool in the line of reflection of the zig-zag beam of light from the other end mirror of said one series.
